SAMPLER FOR BAGGED MATERIALS

Harry Friedman, Twin Falls, Idaho

Application May 9, 1938, Serial No. 206,963

6 Claims. (Cl. 83—15)

The invention relates to a seed trier and more especially to samplers for bagged materials.

The primary object of the invention is the provision of a device of this character, wherein through the use of a plurality of springy tines grouped about the piercing end of a sampler or trier tube and a gauge, the said tines will be limited in their insertion in the interstices present between the strands of a weaved container such as a bag, sack or the like filled with seed, either grain or other material, without excessive disturbance of the strands or the damaging of the same and confine the weave at the point of the piercing of the sampler or trier tube through the fabric of the said container, yet allowing displacement of the strands of the weave for accommodation of the sampler or trier tube for the entry into the contents of said container without damaging the weave or permanently leaving an opening in the container on withdrawal of the sampler or trier tube therefrom, the sampler or trier tube being for the sampling of the contents of the container in the usual well-known manner in that a quantity of the contents is taken up and held by such tube for easy inspection thereof on withdrawal from the bagged material.

Another object of the invention is the provision of a device of this character, wherein the sampler or trier tube can be readily and easily inserted into material within a container such as a bag, sack or the like to the desired extent for assuring the obtaining of a quantity of such material for its inspection, and such material can be readily tested, not only as to size and condition of the grain, but at any particular part or portion thereof and thus arriving at a fair test, the sampler or trier tube when being forced through the container for entry to the bulk of its contents the fabric of such container will be maintained in approximately the original state of weave yet the strands being susceptible of displacement temporarily for the admission of the sampler or trier tube into the bulk of the contents of said container and in a manner to eliminate permanency of a hole therein on withdrawal of the sampler or trier tube from the container and its contents and in this way preserving the weave of the container without resultant damage thereto by the piercing operation required of the sampler or trier tube.

A further object of the invention is the provision of a device of this character, wherein the construction thereof in its entirety is novel, being susceptible of easy handling for the sampling operation thereof and assures against damage to

the container through temporary puncturing thereof for sampling purposes.

A still further object of the invention is the provision of a device of this character, which is simple in its construction, thoroughly reliable and effective in operation, convenient for application to and removal from the work, durable and inexpensive to manufacture.

With these and other objects in view, the invention consists in the features of construction, combination and arrangement of parts as will be hereinafter more fully described and illustrated in the accompanying drawings, which disclose the preferred embodiment of the invention, and pointed out in the claims hereunto appended. 15

In the accompanying drawings:

Figure 1 is an elevation of the device constructed in accordance with the invention.

Figure 2 is a sectional view taken on the line 2—2 of Figure 1 looking in the direction of the arrows.

Figure 3 is a fragmentary sectional view showing the sampler or trier tube in adjusted position and piercing a container carrying a bulk of material, for sampling of the latter. 25

Figure 4 is an elevation of the device with the parts adjusted to the position shown in Figure 3.

Figure 5 is a sectional view on the line 5—5 of Figure 2 looking in the direction of the arrows.

Figure 6 is a sectional view taken on the line 6—6 of Figure 2 looking in the direction of the arrows. 30

Figure 7 is a sectional view taken on the line 7—7 of Figure 3 looking in the direction of the arrows. 35

Figs. 8 and 9 are views showing respectively outer and inner spreading tines.

Similar reference characters indicate corresponding parts throughout the several views in the drawings. 40

Referring to the drawings in detail, the device comprises a sampler or trier tube 10 having an outwardly tapered pointed piercing end 11, the extreme pointed tip 12 thereof being solid for effective piercing operation while adjacent to this tip is an elongated opening 13 which allows the inflow of a quantity of bulk material held within a container, such as a bag, sack or the like, a portion of the bag, sack or the like being indicated at 14, and the strands of its weave are 45 denoted at 15 and 16, respectively. The tube 10 is of straight formation and can be of any desired length for insertion within the bulk of material 17 the required distance for sampling of such material, the sample quantity of the ma- 50

55

terial being delivered into the tube through the opening 13 therein after penetration of the bulk by the tube and subsequent withdrawal of such tube from the bulk, as is common in the use of 5 sampler or trier tubes.

Fixedly held on the tube at the end opposite the tip 12, which end is open as at 18, is a hand knob 19, it being flattened as at 20 to serve as 10 an indicator side thereto indentifying that side having the opening 13 in said tube while slidably fitted upon the straight extent of the said tube 10 is a header or crown stock 21, which is preferably circular in contour and is rounded upwardly in the direction of the knob 19. The tube 15 has formed therein an annular inset stop shoulder 22 with which cooperates a spring ring-like latch 23 fitted within the header or crown 21 to limit the relative movements of the said tube and header or crown in one direction. Surrounding 20 the tube 10 is a coiled expansion spring 24 seated against the header or crown 21 and against the knob or grip 19, and the purpose of this spring is to hold the shoulder 22 normally engaged by the latch 23.

25 Carried by the header or crown 21 are slightly outwardly flared spaced opposed wings or cheeks 25, these coacting with each other to function as a gauge and also as a guard hereinafter set forth.

Tufted or otherwise anchored within the 30 header or crown 21 are outer and inner series of times 26 and 27, respectively, these encircling the piercing end of the tube 10 being grouped about the same. The tines of the series are inherently resilient or springy, and normally crowd about 35 the tip 12 of said piercing end of the tube A when disposed inwardly between the wings or cheeks 25, this being the normal position.

Embracing the outer series of tines 26 are the 40 yokes 28 and 29, respectively, these being reversely fitted with relation to each other, and are made fast to the wings or cheeks 25 for the overlapping thereof in a horizontal direction, the wings or cheeks 25 being of slightly different lengths with respect to each other so as to have 45 an overlapped relationship between the yokes 28 and 29 in their reversely extended positions inwardly of the said wings or cheeks. The purpose of the yokes is to limit the spread of the outer series of tines 26 in the operation of the device 50 while the yoke 28 functions as a gauge to limit the penetration or insertion of the outer ends of the tines 26 and 27 when the device is brought into a set position against the bag exteriorly thereof when carrying bulk material and thus 55 said yoke functions as a gauge, this positioning of the device being shown in Figures 2 and 3 of the drawings.

In the use of the device, after the setting thereof with relation to the bag, when the tube 10 is 60 pushed upon, its piercing end 11 scatters the tines 26 and 27 in that the piercing end 11 will urge such tines out of its path of movement when penetrating the bulk of material within the bag, and in doing this the tines 26 and 27 65 become active upon the strands 15 and 16 of said bag, sack or the like, the outer ends of the tines being carried through the interstices between the strands or within the weave thereof, and thus temporarily effecting, through the displacement 70 of such strands, an opening in the bag, sack or the like body for the passing of the tube 10 within the bulk therein for sampling operation, and without damaging the strands 15 and 16 during such operation of the device. Now when the tube 75 10 is extracted or removed from the bulk 17 of

material within the bag, sack or the like, the tines 26 and 27 return to normalcy and thus effect the closing of the temporary opening created within the body of said bag.

The tines 27 are of outward tapered formation 5 and are heavier than the tines 26 which are straight and of pin shank-like formation.

Swingable from the knob 19 at diametrically opposite sides of the tube exteriorly thereof are spring-tensioned latching arms 30; the tensioning springs being indicated at 31, and the pivots are indicated at 32 swingingly connecting the said arms to the knob 19. These arms normally engage with the header or crown 21, being forced inwardly by the springs 31 for such engagement, 15 and in this manner the tube 10 is held against relative movement with respect to the header or crown 21, thus enabling the engagement of the tines 26 and 27 in the body of the bag, sack or the like 14 before effecting the piercing of the latter and the bulk 17 of material therein by the tube 10, in that the piercing end 11 is well within the series of tines 26 and 27 and confined between the wings or cheeks 25, which is the normal position of the said tube 10.

It is required that the arms 30 be initially moved from contact with the header or crown 21 when it is desired to operate the tube 10 for the piercing action thereof in penetrating the bag, sack or the like 14 and the bulk 17 therein.

When the tube 10 accumulates a quantity of the material for sampling or testing purposes, by upsetting the device after removal from sample gathering activity thereof the quantity of material collected thereby can be discharged through the open end 18 of said tube for inspection and test purposes. During the penetrating or piercing operation of the device the air within the tube 10 is dispelled through the open end 18, for the inflow of a quantity of material through the slot 13 in the piercing end 11 of the said tube.

Through the activity of the tines 26 and 27, the strands 15 and 16 of the body of the bag, sack or the like 14 will become set to normalcy, thus eliminating a permanent opening in the bag, sack or the like, as a temporary opening is created resultant from the insertion of the piercing end 11 of the tube 10 into the bag body for the sampling operation of the device.

The wings or cheeks 25 are rigid and permanently secured to the header or crown 21, the tube 10 being manually moved relative to the header or crown 21 and in the use thereof it is pushed inwardly of said header or crown for the forcing of the piercing end 11 through the body of the bag, sack or the like into the bulk 17 of material whence a quantity of the latter will flow through the opening 13 for the collecting thereof within the tube 10 to allow inspection or testing of such material.

What is claimed is:

1. A device of the character described comprising a tube having a slotted pointed piercing end and an opposite open end, a header slidably riding said tube, a pair of opposed cheeks carried by and extending from said header, a plurality of inherently resilient tines fitted with said header and crowded about the piercing end of said tube, means on the cheeks for holding the tines in their crowded relationship to the piercing end of the tube and allowing displacement thereof by movement of the tube, and means arranged between the header and the tube for latching the latter against movement in one direction relative to said header.
2. A device of the character described compris-

ing a tube having a slotted pointed piercing end and an opposite open end, a header slidably riding said tube, a pair of opposed cheeks carried by and extending from said header, a plurality of inherently resilient tines fitted with said header and crowded about the piercing end of said tube, means on the cheeks for holding the tines in their crowded relationship to the piercing end of the tube and allowing displacement thereof by movement of the tube, means arranged between the header and the tube for latching the latter against movement in one direction relative to said header, and yieldable means active upon the tube for normally holding the same in a latched position with respect to said header.

3. A device of the character described comprising a tube having a slotted pointed piercing end and an opposite open end, a header slidably riding said tube, a pair of opposed cheeks carried by and extending from said header, a plurality of inherently resilient tines fitted with said header and crowded about the piercing end of said tube, means on the cheeks for holding the tines in their crowded relationship to the piercing end of the tube and allowing displacement thereof by movement of the tube, means arranged between the header and the tube for latching the latter against movement in one direction relative to said header, yieldable means active upon the tube for normally holding the same in a latched position with respect to said header, and spring tensioned arms fitted with the tube and movable to engagement with the said header.

4. A device of the character described comprising a tube having a slotted pointed piercing end and an opposite open end, a header slidably riding said tube, a pair of opposed cheeks carried by and extending from said header, a plurality of inherently resilient tines fitted with said header and crowded about the piercing end of said tube, means on the cheeks for holding the tines in their crowded relationship to the piercing end of the tube and allowing displacement thereof by movement of the tube, means arranged between the header and the tube for latching the latter against movement in one direction relative to said header,

yieldable means active upon the tube for normally holding the same in a latched position with respect to said header, spring tensioned arms fitted with the tube and movable to engagement with the said header, and a knob at the open end 5 of the tube and having a flattened indicator face matching that side of the piercing end of said tube having the slot therein.

5. A device of the character described comprising a tube having a slotted pointed piercing end 10 and an opposite open end, a header slidably riding said tube, a pair of opposed cheeks carried by and extending from said header, a plurality of inherently resilient tines fitted with said header and crowded about the piercing end of said tube, 15 means on the cheeks for holding the tines in their crowded relationship to the piercing end of the tube and allowing displacement thereof by movement of the tube, means arranged between the header and the tube for latching the latter against 20 movement in one direction relative to said header, yieldable means active upon the tube for normally holding the same in a latched position with respect to said header, spring tensioned arms fitted with the tube and movable to engagement with the said 25 header, and a knob at the open end of the tube and having a flattened indicator face matching that side of the piercing end of said tube having the slot therein, the said tines being disposed in series of different sizes with respect to each other and both 30 series being extended a slight distance beyond the outermost ends of said cheeks.

6. A device of the character described comprising a plurality of inherently resilient tines, supporting means for the same and holding them in 35 bundled relationship with their pointed extremities positioned for piercing the wall of a fabric container between the strands of the fabric, and an open tubular pointed member insertable axially through the bundled tines for springing the 40 latter laterally and thereby imposing pull on the strands of fabric and effecting an opening in the latter for the entrance of the pointed end of said tubular member.

HARRY FRIEDMAN. 45
